UNITED STATES PATENT OFFICE.

THOMAS S. PATTERSON, OF ROSEMONT, PENNSYLVANIA.

ABDOMINAL SUPPORTER.

1,068,268.

Specification of Letters Patent.

Patented July 22, 1913.

Application filed June 23, 1908. Serial No. 439,973.

To all whom it may concern:

Be it known that I, THOMAS S. PATTERSON, a subject of the King of Great Britain and Ireland, residing in Rosemont, Pennsylvania, have invented certain Improvements in Abdominal Supporters, of which the following is a specification.

The object of my invention is to so construct an abdominal supporter as to relieve 10 the back of the wearer entirely of the weight carried by the supporter and transfer the weight to the shoulders, as fully described hereafter, reference being had to the accompanying drawing, in which:—

15 Figure 1, is a perspective view of my improved abdominal supporter; Fig. 2, is a side view showing the supporter applied; and Figs. 3 and 4, are views of modifications of the means for holding the lower end 20 of the supporter in position.

A is the supporter shaped to conform to the abdomen and made of any suitable fabric of a type either elastic or inelastic as desired. This supporter is practically in 25 the form of a sling passing around the extended portion of the abdomen so that the line of support is from the shoulders of the wearer instead of the back as heretofore.

At each upper corner *a* of the supporter 30 are buttons *b* in the present instance, to which are attached the loops *c* of a suspending band *C*. This band is preferably made as clearly shown in Fig. 1, the portion *c'* on one side extends over the shoulder across 35 the back and is attached to the other suspender at *c*²; while the other section *c*² of the suspender extends over the other shoulder across the back and is attached at *c*⁴ to the first mentioned suspended. Thus the 40 supporter is carried wholly by the shoulders and the supporter is so made that the weight will be in a direct line with the suspender, as indicated by dotted line *x—x*, Fig. 2, taken from the top of the shoulder to the 45 lower portion of the abdomen. Thus the back is entirely relieved of pressure, as the extra weight of the abdomen and the supporter are carried entirely by the shoulders.

In order to hold the lower portion *a'* of 50 the supporter in place I preferably form loops *D*, *D* which are shaped to fit around

the limbs of the wearer; the inner portions of the loops being attached at *d* at the base of the supporter while the outer portions of the loops are attached at *d'* some distance 55 from the lower portion, as illustrated in Fig. 2, thus retaining the supporter in position.

Other means of retaining the lower portion of the supporter may be used without departing from my invention. For instance, 60 I have shown in Fig. 3, an elastic band *D'* adapted to the limb of the wearer and attached at *d*² to the supporter *A*; while in Fig. 4, I have shown a fabric strap *D*² extending from the point *d*² of the supporter 65 A between the limbs and attached to an extension *C'* of the suspender *C*, but other means may be provided for holding the lower end of the supporter in place.

Heretofore abdominal supporters have 70 been so arranged as to encircle the body and while shoulder straps have been used to retain the supporters in position the weight in every case has been carried by the back and in most cases at the small of the back, 75 consequently while the supporters relieve the weight at the front of the wearer the weight was concentrated at the back and great pain resulted at this point, and in many cases supporters of this type could 80 not be used in view of the above fact.

My improved supporter is shaped simply to inclose the projecting forward portion of the body, leaving the back entirely free and the line of strain, as indicated by the dotted 85 line in Fig. 2, is practically midway between the upper and lower portions of the supporter and the loops or other attachments are used for the purpose of retaining the lower portion of the supporter in position 90 and preventing it riding up out of position.

I claim:—

A supporter of substantially triangular shape adapted to fit the abdominal portion of the body, said supporter having a substantially straight top and downwardly converging sides terminating substantially at a point at the bottom, suspenders connected to the side portions of said supporter and passing over the shoulders, the connections for such suspenders being forward of 95 a vertical line drawn substantially through 100

the center of the body whereby said suspenders serve to hold the supporter close to the body and form the sole support for the abdomen in a direct line from the shoulders, 5 and retaining means connected to the lower portion of the supporter and passing rearwardly between the legs.

In testimony whereof, I have signed my name to this specification, in the presence of two subscribing witnesses.

THOMAS S. PATTERSON.
